[57] CLAIM

The ornamental design of a liquid soap dispenser or the like, as shown and described.

DESCRIPTION

FIG. 1 is a perspective view of a liquid soap dispenser or the like showing my new design;

FIG. 2 is a front elevational view thereof;

FIG. 3 is a right side elevational view thereof, the left side being a mirror image of that shown;

FIG. 4 is a top plan view thereof;

FIG. 5 is a bottom plan view thereof; and

FIG. 6 is a rear elevational view thereof.
